H. M. CAWOOD

GAS STOVE

Filed Nov. 22, 1924

FIG. 1.

FIG. 2.

FIG. 3.

Inventor

H. M. Cawood.

By

A. Randolph, Jr.
Attorney

UNITED STATES PATENT OFFICE.

HORACE M. CAWOOD, OF LOS ANGELES, CALIFORNIA.

GAS STOVE.

Application filed November 22, 1924. Serial No. 751,632.

To all whom it may concern:

Be it known that I, HORACE M. CAWOOD, a citizen of the United States, residing at Los Angeles, in the county of Los Angeles 5 and State of California, have invented certain new and useful Improvements in Gas Stoves; and I do hereby declare the following to be a full, clear, and exact description of the invention, such as will enable others 10 skilled in the art to which it appertains to make and use the same.

The present invention provides a stove adapted for use in heating and cooking, said stove being light, portable, and adapted to 15 use gas as fuel, and of such construction as to prevent a fatality in the event of the flame being extinguished from any cause, the stove being connected to a chimney or like outlet which carries off fumes, uncon- 20 sumed gas, and noxious odors, said stove also being constructed to give a maximum amount of heat for cooking or warming a room which would otherwise be uncomfortable when chilled.

25 Other objects and advantages will be apparent and suggest themselves as the nature of the invention is understood.

While the drawings illustrate an embodiment of the invention it is to be understood 30 that in adapting the same to meet different conditions and requirements, various changes in the form, proportion and minor details of construction may be resorted to without departing from the nature of the 35 invention.

Referring to the accompanying drawings 40 forming a part of the specification,

Figure 1 is a top plan view of a gas stove 45 embodying the invention,

Figure 2 is a front view thereof, and

Figure 3 is a sectional view on the line 3-3 of Figure 1.

Corresponding and like parts are referred 45 to in the following description and designated in the several views of the drawings by like reference characters.

The numeral 1 denotes the body of the stove which is hollow and shallow so that the distance between the top 2 and the bottom 50 3 is approximately about two inches, and the breadth of the stove may be of any extent depending upon the capacity and particular purpose for which the same is de-

signed. An air inlet 4 is provided in a side 55 of the stove body and is preferably located at the front and opposite the vent pipe 5 which is connected to the rear portion of the top 2 and which is connected to a chimney (not shown) or other outlet to admit of the fumes, unconsumed gas, and the like, 60 escaping into the open air thereby preventing contamination of the air of the room in which the stove may be located. A burner 6 is located within the body of the stove and a fuel pipe 7 connects therewith and is provided in its length with a valve 8, said pipe leading from any source of supply such as 65 a gas main.

The body of the stove is mounted upon a suitable base or support which as shown 70 comprises a lower frame 9, an upper frame 10, posts 11 connecting the two frames, and dowels or pins 12 projecting upwardly from the top frame 3 and entering openings in the bottom 3 so as to prevent displacement 75 of the body from the support or stand.

In the preferable construction, the body 80 consists of sheet metal and when the burner is lighted the heat is reflected from all parts of the body and is utilized to the best possible advantage for heating and cooking, the fumes and odors being carried off through the vent pipe 5 and the gas also finding an outlet through the vent pipe 85 should the flame become extinguished from any cause.

What is claimed is:

A gas stove comprising a stand, a shallow hollow body mounted upon the stand 90 and having an inlet air opening in its front and a vent pipe connected with the rear portion of its top, and a burner disposed within the body, the stand comprising similar upper and lower frames and connecting 95 posts, and said stand having dowels or pins projecting from its top to enter openings in the bottom of the stove body to hold the parts when properly assembled.

In testimony whereof I affix my signature in presence of two witnesses.

HORACE M. CAWOOD.

Witnesses:

LELIA P. CHILDERS,
LEE MILES.
